UNITED STATES PATENT OFFICE.

WELFORD G. EDWARDS, OF PLAINVIEW, MINNESOTA.

SLEIGH.

No. 874,750.

Specification of Letters Patent.

Patented Dec. 24, 1907.

Application filed March 25, 1907. Serial No. 364-322.

To all whom it may concern:

Be it known that I, WELFORD G. EDWARDS, a citizen of the United States, residing at Plainview, in the county of Wabasha, State 5 of Minnesota, have invented certain new and useful Improvements in Sleighs; and I do hereby declare the following to be a full, clear, and exact description of the invention, such as will enable others skilled in the art 10 to which it appertains to make and use the same.

This invention relates to new and useful improvements in sleighs, and has particular reference to a sleigh embodying interconnected rear and front sleds.

In connection with a sleigh of the above type, the invention aims as a primary object to provide novel yieldable connections between the front and rear sled, whereby the 20 latter will have a tendency to ride upwardly instead of to dig downwardly as is ordinarily the case.

The invention aims as a further object to provide a novel resilient connection between 25 the body of the sleigh and the sleds, whereby the tendency of the latter to rock or swing laterally is reduced to a minimum degree, and whereby the strain upon the resilient connection elements is reduced to a minimum 30 degree.

The invention aims as a further object to provide in connection with the sleds embodied in the present invention, a novel "knee" iron, interposed between the runners and the beams of such sleds.

The invention aims as a further object to provide resilient connections between the interconnected parts, which will serve to absorb and cushion the direct and reactionary 40 shocks and vibrations incident to travel.

The invention finally aims to provide a sleigh of the above type which will be comparatively inexpensive to manufacture, simple in construction and practical and efficient 45 in use.

The detailed construction will appear in the course of the following description, in which reference is had to the accompanying drawings forming a part of this specification, like characters of reference designating similar parts throughout the several views, wherein:

Figure 1 is a side elevation of a sleigh constructed in accordance with the present invention. Fig. 2 is a top plan view of the 55 ends of such sleigh, the body thereof being

removed. Fig. 3 is a front plan view of the rear sled, the runners being shown in section. Fig. 4 is a similar view of the front sled. Fig. 5 is an enlarged fragmentary vertical 60 section of a cushioning connection between such front beam and one of the runners. Fig. 6 is an enlarged detailed perspective view of a crank arm included in the connecting means above referred to, together with 65 fragmentary illustrations of the associated parts of such crank arms.

The invention in its practical embodiment comprises a body 1, from which are supported the front sled 2 and the rear sled 3. The 70 supporting means of the front sled 2, includes a large fifth wheel 4, whereby said front sled may be turned with relation to the rear sled and the body, to direct the travel of the sleigh.

The sleds 2 and 3 are constituted of runners 5 carrying on their underneath surfaces the usual shoes 6. At the rear portions of each of the runners 5, are arranged vertically extending knee irons 7 which conjointly support transverse rear beams 8. The rear beams 8 are provided adjacent their outer ends with bearings 9, which afford journals for the central portions of crank arms 10, the laterally extending portions of which are disposed adjacent the top of the knee irons 7. The lower movable member of the fifth wheel 4 carries parallel cleats 11 and similar cleats 12 are provided upon the rear portions of the body 1. Parallel leaf springs 13 are fixed 80 centrally thereof to the respective cleats 11 and 12, and the free ends of said leaf springs are bent to form sleeves 14, through which the projecting ends of the crank arms 10 are passed.

The front sled 2 carries between the front end of its runners 5 a transverse beam 15, upon which is provided a tongue 16 reinforced by diagonal braces 17, and carrying doubletrees 18. Between the front ends of 100 the runners 5 of the rear sled 3, a rearwardly curved front beam 19 is supported. The beam 19 is reinforced by a coincident curved metallic back member 20, through the projecting ends of which headed bolts 21 are 105 passed. The beam 19 is of less width than the distance between the runners 5 of the sled 3, and is connected to said runners by the bolts 21, which include cushioning elements. To this end expansive coil springs 22 are 110 interposed between the heads of the bolts 21 and the projecting ends of the back member

20. Nuts 23 are likewise interposed between said projecting ends and the runners 5. It will thus be seen that the connection afforded by the back member 20, the bolts 21 and the 5 springs 22, permits of the front beam 19 yielding laterally on either side with relation to the runners 5. Such lateral yielding action is of advantage owing to the fact that the rear sled 3 is connected to the front sled 10 2, and that the oscillation of the front sled incident to travel, is taken up or absorbed by the front beam 19 without being imparted to the rear sled 3 as an entirety.

The connection between the front and rear 15 sleds is illustrated in Fig. 5, and comprises a tubular member 24 having at its rear end furcations 25, which at their ends are fixed to the beam 19 of the sled 3. Within the member 24 is a rod 25 terminating at its rear end 20 in a head 26 and at its front end in a hook 27. Surrounding the rod 25 is a thimble 28 which is threaded, as at 29, upon the front end of the member 24. An expansive coil spring 30 likewise surrounds the rod 25 within the 25 member 24, and with one end bears against the head 26 and with its other end bears against the thimble 28. The hook 27 is engaged with a similar hook or eye 31 carried centrally upon the rear face of the beam 8 of 30 the front sled 2.

The knee irons 7 above mentioned, are of inverted V-shape, and include depending divergent legs 32, terminating at their lower ends in angular apertured bifurcations 33, 35 which are fixed to the runners 5 adjacent thereto by fastening means 34. The furcations 33 are in fact extensions of the angular sides of the legs 32, the latter being bent into angle iron shape, as shown in Figs. 3 and 4, in 40 order that their structure may be strengthened. The legs 32 at their upper ends are united by an integral horizontal bridge piece 35, to which is fixed a cap plate 36, having upstanding sides 37 which overlie the sides of 45 the beams 5, and which are fixed to said beams by fastening means 38.

The advantages set forth in the preamble will be readily apparent from the foregoing 50 description. The member 24 constitutes a short tongue between the sleds 2 and 3 and owing to its hinged connection with the sled 2, serves to draw the rear sled from the nose of the runners. The tension is on the coil spring 30, and is absorbed by such spring during 55 the oscillations of the front sled. When the front sled oscillates downwardly, it increases the tension of the spring 30, and when it oscillates upwardly, it releases such tension, thus eliminating shocks and vibrations in

riding over rough roads and affording a noiseless joint. In traveling in deep snow, the drag of the rear sled is decreased owing to its tendency to climb on top of the snow instead of digging into the same as previously explained.

Another important feature of the invention resides in disposing the ends of the springs 13 in a plane coincident with the bridge piece 35 of the knee irons 7. Such arrangement reduces the tendency of the beams 70 to rock back and forth and consequently reduces the strain upon the springs 13.

From the foregoing description, it will be seen that simple and efficient means are provided for accomplishing the objects of the 75 invention, but while the elements herein shown and described are well adapted to serve the functions set forth, it is obvious that various minor changes may be made in the proportions, shape and arrangement of 80 the several parts, without departing from the spirit and scope of the invention as defined in the appended claims.

What is claimed is:

1. In a sleigh, the combination with a 85 body, a front steering sled and a rear fixed sled, of a connection between said sleds comprising a tubular member fixed to the rear sled, a member slidable within said tubular member, a thimble threaded on said tubular member and surrounding said slidale member, said slidale member having a head at one end and a hook at the other end, an expansive coil spring surrounding said slidale member within said tubular member and 95 bearing against said head and said thimble, and a hook carried by said steering sled for engagement with said first named hook.

2. In a sleigh, the combination with a 100 body, a front steering sled and a rear sled 100 connected thereto, of a beam disposed between the front ends of the runners of said rear sled, a back member fixed to said beam and having projecting ends, headed bolts projected through said ends and through the 105 ends of the runners adjacent thereto, nuts on the outer ends of said bolts, expansive coil springs interposed between said projecting ends and the headed ends of said bolts, and a connection between said beam and the front sled.

In testimony whereof, I affix my signature, in presence of two witnesses.

WELFORD G. EDWARDS.
